SPOON

Carl J. Lind, Evanston, Ill.

Application November 25, 1952, Serial No. 22,437

Term of patent 14 years

(Cl. D54—12)

Figure 1 is a plan view of a spoon embodying my new design, the bowl of the spoon being shown in dotted lines;

Fig. 2 is a side elevational view thereof;

Fig. 3 is a bottom plan view of the spoon, a portion thereof being broken away for convenience of illustration.

Fig. 4 is an enlarged cross-sectional view taken substantially on the line 4—4 in Fig. 3; and

Fig. 5 is a similar view taken on the line 5—5 in Fig. 3.

The dominant features of the design are shown in full lines in the drawing.

I claim:

The ornamental design for a spoon, substantially as shown and described.
